UNITED STATES PATENT OFFICE.

AARON H. BEDLE, OF DAYTON, OHIO.

DESIGN FOR A JELLY-WAFFLE FORK.

SPECIFICATION forming part of Design No. 33,415, dated October 23, 1900.

Application filed September 27, 1900. Serial No. 31,332. Term of patent 7 years.

To all whom it may concern:

Be it known that I, AARON H. BEDLE, a citizen of the United States of America, residing and having my post-office address in 5 Dayton, in the county of Montgomery and State of Ohio, have invented and produced a certain new and original Design for a Jelly-Waffle Fork; and I hereby declare that the following is a clear, full, and exact description thereof, reference being had to the accompanying drawing, in which like numerals refer to like parts.

The figure of the drawing represents a perspective view of a jelly-waffle fork embodying my invention and design.

The leading feature of my design consists of a member having a plurality of waffle-cores and a handle projecting therefrom. 14 represents said member, having the plurality of waffle-cores 15 and a handle 16 projecting 20 therefrom.

Having now described my invention and design, what I claim is—

The design for a jelly-waffle fork, substantially as shown and described. 25

In witness whereof I have hereunto set my hand this 25th day of September, 1900.

AARON H. BEDLE.
